(57) **CLAIM**

The ornamental design for a combined fishing glove and belt apparatus, as shown and described.

DESCRIPTION

FIG. 1 is a front perspective view of the combined fishing glove and belt apparatus showing my new design;
FIG. 2 is a side elevation view, shown in use;
FIG. 3 is another side elevation view, shown in use;
FIG. 4 is another side elevation view, with the glove shown removed from the clothing protector;
FIG. 5 is a partial enlarged view of the belt, showing the male/female closure;
FIG. 6 is another partial enlarged view of the rear of the belt;
FIG. 7 is a partial view of the opposite side of the belt, showing the retractor with the needle nose pliers attached;
FIG. 8 discloses a side view, with the design shown in use;
and,
FIG. 9 is another side view, with the design show in use.

The broken line showing of environment in the drawings is included for the purpose of illustrating only and forms no part of the claimed design.

FIGS. 5-7 are shown broken away for convenience of illustration. The inner portion of the belt (not shown) is plain and unornamented.
